UNITED STATES PATENT OFFICE.

HERMANN DANIEL RUDOLPH GUMTOW, OF BERLIN, GERMANY, ASSIGNOR
TO M. LUTZNER AND H. GUMTOW, OF SAME PLACE.

JET APPARATUS.

SPECIFICATION forming part of Letters Patent No. 373,931, dated November 29, 1887.

Application filed January 8, 1886. Serial No. 188,047. (No model.)

To all whom it may concern:

Be it known that I, HERMANN DANIEL RUDOLPH GUMTOW, of the city of Berlin, Kingdom of Prussia, German Empire, have invented 5 certain new and useful Improvements in Jet Apparatus, of which the following is a specification.

The object of my invention is to provide a new and improved jet apparatus for delivering water in fine jets within a tube, for the purpose of producing suction or air-pressure, and thus removing foul air from rooms or forcing pure air into the rooms, as may be desirable.

15 The invention consists in various constructions and combinations of parts and details, as will be fully described and set forth herein-after.

In the drawings, Figure 1 is a cross-sectional elevation of a tube, showing my improved jet apparatus in position. Fig. 2 is a detail cross-sectional view of the jet apparatus.

Similar letters of reference indicate corresponding parts.

25 The water-jet apparatus consists of the annular pipe or ring A, having the outwardly inclined apertures B in the bottom, which guide the water-jets outward and downward at an inclination and against the walls of an air-tube, C, in which the water pipe or ring A is placed.

D is a branch water-pipe provided with the nozzle E at right angles to the plane of the

water pipe or ring A, and in the center of the same, which nozzle throws a central jet of 35 water through the ring, the jets from said nozzle striking against the rebounding spray of the walls of the air-tube.

If the jet apparatus is placed in a position shown on the right-hand side of Fig. 1, it creates 40 a downward current or air-suction in the right-hand end or shank of the air-tube C and draws the air from the room.

If the jet apparatus is placed in a position shown at the left of Fig. 1, it creates a downward current in the left-hand shank of the air-tube C and forces the air into the room. 45

Having thus described my invention, I claim as new and desire to secure by Letters Patent—

In a water-jet apparatus, the combination 50 of an air duct or tube surrounding the spraying device, an annular water pipe or ring having outwardly-inclined apertures for guiding jets of water against the walls of the air-tube, and a branch water-pipe provided with a nozzle for directing a central jet of water through the ring against the rebounding spray from the walls of the air-tube, substantially as described. 55

In testimony that I claim the foregoing as my 60 invention I have signed my name in the presence of two subscribing witnesses.

HERMANN DANIEL RUDOLPH GUMTOW.
